STORAGE BATTERY CONNECTER

Antonin Rocheleau, Cap-de-la-Madeleine,
Quebec, CanadaApplication February 23, 1935, Serial No. 7,668
In Canada July 6, 1934

3 Claims. (Cl. 173—259)

The present invention pertains to a novel connector designed for use in storage batteries, particularly of the type used on motor vehicles.

The object of the invention is to provide a simple device of this character which clamps on the battery post in opposite directions or in a scissors-like manner, and which is also readily accessible for attachment and detachment. In the accomplishment of these objects, the device consists of a pair of clamping plates formed each with an over-sized aperture with respect to the post on which the plates are to be mounted. The plates are formed respectively with upstanding bosses or knuckles which come into alignment when the plates are properly mounted. The clamping pressure is initiated by a bolt passed through the aligned knuckles and having a tightening nut thereon. Inasmuch as the bosses or knuckles stand up from the respective plates, the plates themselves do not interfere with the accessibility of the bolt and nut. Further, the knuckles are so mounted that a space remains between them, exposing a portion of the bolt, when the device is assembled on the battery post. In battery practice, the parts often become so corroded and coated that the clamp cannot readily be removed. In replacing such a clamp, according to the present invention, it is not essential to remove the nut. The exposed part of the bolt between the knuckles may be cut by means of a hack saw or bolt cutter, whereupon the clamp may readily be removed.

The invention is fully disclosed by way of example in the following description and in the accompanying drawing in which—

Figure 1 is a plan view of the device applied to a battery post, the latter being shown in section;

Figure 2 is an elevation of the device on a battery post;

Figure 3 is a similar elevation at right angles to Figure 2;

Figure 4 is a perspective view of one of the clamp plates; and

Figure 5 is a perspective view of the other clamp plate.

Reference to these views will now be made by use of like characters which are employed to designate corresponding parts throughout.

In Figure 4 is shown the clamp plate 1 which occupies the lower position, as may be seen by reference to Figures 2 and 3. This plate is of substantially square formation and has a central aperture 2 which is somewhat larger than the

battery post to be received therein, for a purpose which will presently appear. At one of the corners is formed an upstanding boss or knuckle 3 which functions as a part of the clamping mechanism as will also presently be described. At the diagonally opposite corner is formed an integral lug or hook 4 projecting slightly over the top of the plate 1 parallel to the axis of the knuckle 3.

The upper clamp plate 5 is also of substantially square formation and about the same size as the plate 1. The plate 5 is likewise formed with a central aperture 6 adapted to coincide with the aperture 2 of plate 1 when the plates are superimposed, and the aperture 6 is also slightly larger than the post to be received therein. At one of the corners of the plate 5 is formed an upstanding boss or knuckle 7 similar to the member 3 and adapted to align axially therewith when both plates are assembled on a battery post, as may be seen in Figures 1, 2, and 3. From the center of the edge opposite the member 7, projects a lug 8 formed at its outer end with a grooved lip 9 for a purpose which will presently be described.

Figures 2 and 3 shows a conventional battery post having a conical portion 10 surmounted by a cylindrical portion 11 as may also be seen in Figure 1. The clamp plates are mounted successively on the portion 11, first the plate 1 and then the plate 5, as already indicated. It is to be noted, however, that the plates are so mounted that the knuckles 3 and 7 thereof project upward and stand in alignment with each other, as may be seen in Figures 1, 2 and 3. It has already been stated that the apertures 2 and 5 of the plate are larger than the part of the post which they receive, and it will be noted in this connection that the part of the post here involved is the cylindrical part 11 of uniform circumference. In the assembly in the manner described, the lug 8 of plate 5 is received partly beneath the hook 4 of plate 1, the hook serving as a hold-down member in this relation to maintain the plates in mutual surface contact.

A headed bolt 12 is now passed through the aligned knuckles 3 and 7, and the latter are drawn together by means of a nut 13 on the threaded end 14 of the bolt. The over-size of the apertures 2 and 6 with relation to the post 11 affords a slight shifting of the plates 1 and 5 as the nut 13 is tightened on the bolt 12. This movement is in the nature of scissors action wherein opposite edges of the apertures, respectively, bite into the post 11 at substantially dia-

metrically opposite points, as shown in dotted lines in Figure 1. Finally, the usual cable is soldered in the lip 9 in the usual manner.

Due to the upstanding position of the lugs 3 and 7, the bolt and nut lie at a higher level than the plates 4 and 5. Consequently these plates do not interfere with the accessibility of the bolt and nut, and the clamp as a whole is thereby made easier than usual to apply and remove. In the event that the parts become corroded or coated, as is often the case in battery practice, to such an extent that the nut cannot readily be removed, the bolt itself may be cut at the space which remains between the knuckles 3 and 7, as indicated by the numeral 15 in Figure 1. A hack saw or bolt cutter may be used for this purpose. The various parts of the connector may be made of brass or other suitable metal dipped in tin or lead to prevent attack by the acid in the battery or the fumes issuing therefrom.

Although a specific embodiment of the invention has been illustrated and described, it will be understood that various alterations in the details of construction may be made without departing from the scope of the invention, as indicated by the appended claims.

What I claim is:

1. A battery connection comprising a pair of superimposed plates apertured to be received on a battery post, an upstanding knuckle formed on each plate and adapted for alignment with the other knuckle, a bolt passed through said knuckles for drawing the same together, a lug projecting from one edge of one of said plates,

and a hook formed at the corresponding edge of the other plate and adapted to interlock with said lug for maintaining said plates in surface contact.

2. A battery connection comprising a pair of superimposed plates apertured to be received on a battery post, an upstanding knuckle formed on each plate and adapted for alignment with the other knuckle, a bolt passed through said knuckles for drawing the same together, a lug projecting from one edge of said plates, a hook formed at the corresponding edge of the other plate and adapted to interlock with said lug for maintaining said plates in surface contact, and a lip formed at the end of said lug for attachment of a cable thereto.

3. A battery connection comprising a pair of superimposed plates apertured to be received on a battery post, an upstanding knuckle formed on each plate and adapted for alignment with the other knuckle, and a bolt passed through said knuckles for drawing the same together, a lug projecting from one edge of said plates, a hook formed at the corresponding edge of the outer plate and adapted to interlock with said lug for maintaining said plates in surface contact, said knuckles being spaced apart when the plates are superimposed, thereby exposing a portion of said bolts, in combination with a battery post received in the apertures of said plate and of smaller diameter than said apertures, whereby said plates exert a scissors-like action on said post when said bolt is tightened.

ANTONIN ROCHELEAU.
